UNITED STATES PATENT OFFICE

166,787

TELEVISION CABINET CONTROL PANEL

Samuel E. Adler, Chicago, Ill., assignor to Admiral Corporation, Chicago, Ill., a corporation of Delaware

Application February 9, 1952, Serial No. 18,455

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet Control Panel, of which the following is a specification, reference being had to the accompanying drawings, forming part thereof.

Fig. 1 is a front elevational view of a television cabinet control panel, embodying my new design;

Fig. 2 is a top plan view thereof;

Fig. 3 is a sectional view on line 3—3 of Fig. 1;

Fig. 4 is a sectional view on line 4—4 of Fig. 1;

Fig. 5 is a sectional view on line 5—5 of Fig. 1;
and

Fig. 6 is an elevational view of the right hand end as indicated by 6—6 of Fig. 1.

The dominant features of my design reside in those portions shown by full lines in the drawings.

I claim:

The ornamental design for a television cabinet control panel, as shown and described.

SAMUEL E. ADLER.
